UNITED STATES PATENT OFFICE

GEORGE E. PURPLE, OF LA GRANGE, ILLINOIS, ASSIGNOR TO FLEXIBLE STEEL LACING COMPANY, OF CHICAGO, ILLINOIS, A CORPORATION OF ILLINOIS

APPLICATOR FOR METAL FASTENERS

Application filed March 21, 1930. Serial No. 437,664.

This invention relates to improvements in applicators for metal fasteners.

In the art of applying fasteners, such as metallic lacings and hooks, to the ends of belts, it is desirable that a considerable length or number of the fasteners be clinched simultaneously in order to speed up the operation. In the case of larger sizes of fasteners for heavy, thick belts, this result can only be obtained by the use of a great amount of pressure which is not available in the usual plier, anvil or vise attachment types of applicators, heretofore marketed. Furthermore, to perform the clinching operation on successive lengths of fasteners, provision must be made for separating the jaws widely enough to permit the insertion of a new length or series of fasteners before the pressure is again applied to deform or clinch the fasteners and, obviously, these adjustments should be made rapidly even though the application of the final high pressures must necessarily be done relatively slowly through high leverage ratio multiplying means.

One object of my invention is to provide a heavy duty applicator or machine for clinching metal fasteners to the ends of belts, conveyors or the like, the applicator being characterized by the fact that an extremely heavy ultimate pressure may readily be obtained for the final squeezing or clinching operation.

Another object of my invention is to provide an applicator or machine of the type above indicated wherein the adjustments for opening up the jaws for successive operations and the initial clinching or deforming operations, may be done rapidly.

Another object of my invention is to provide a machine of the type indicated where-
40 in the jaw actuators are given a relatively fast initial low leverage ratio movement and a relatively slow final high leverage ratio movement, to thereby clinch the fasteners as quickly as possible.

Still another object of my invention is to provide a machine of the character above set forth which is adapted for operation on different sizes of belt fasteners without any changing of parts, except the readily detachable holders.

Other objects of the invention will more clearly appear from the description and claims hereinafter following.

In the drawings forming a part of this specification, Figure 1 is a top plan view of a machine embodying my improvements. Figure 2 is a front elevational view of the machine shown in Figure 1. In this figure, both dotted and full line positions are shown of certain of the parts. Figure 3 is a side elevation of the machine illustrated in Figure 1. Figure 4 is a vertical sectional view corresponding to the line 4-4 of Figure 1. And Figure 5 is a vertical sectional view corresponding to the line 5-5 of Figure 2.

In said drawings, a main frame is illustrated, the same having base sections 10-10 at each side, front and rear vertically upstanding walls 11-11 and a horizontal table section 12 centrally disposed, said table section having a widened central portion as indicated in the plan view in Figure 1, at 112. The machine also comprises, broadly, a pair of heavy supports 13-13; a pair of actuators 14-14; a pair of slidable jaws 15-15; and a holder 16 for the metal fasteners, together with suitable operating elements and connections, hereinafter described.

Each of the supports 13 is pivotally attached, at its lower forked end, to the base 10 by means of a heavy pivot pin 17. Each support 13 is made of very substantial and rugged construction, preferably in the form of a casting, the same having a main web section 18; vertically extending ribs 19, projecting to the outer side; and approximately horizontally disposed ribs 20-20. On opposite sides of the center, each support 13 is formed with a hub-like section 21 centrally apertured to receive a heavy operating screw 22, the outer surface of each hub 21 providing a bearing surface 23. At its upper end and on the inner face thereof, each support 13 is further provided with a hardened insert 24, of preferably rectangular cross section, said inserts 24 functioning as fulcrums, as hereinafter described.

Each of the actuators 14 is preferably in the form of a substantial casting, forked at its lower end, as indicated at 25-25 and ap-

ertured as indicated at 26 to provide clearance for the screws 22. At its upper end, each actuator 14 has two horizontally and longitudinally extending inserts 27 and 28 therein, the former having a beveled or knife outer surface bearing on the insert 24 of the corresponding support 13. Each insert 28 likewise has a beveled surface on the side facing the center of the machine to serve as a fulcrum bearing for the corresponding adjacent operating link 29, which, along its outer edge, has a special knife edge construction, as best indicated in Figure 4. This knife edge construction consists of a downwardly and outwardly sloping face 30, a relatively narrow face 31 which slopes downwardly and inwardly from the knife edge proper and a third face 32, which slopes downwardly and inwardly but at a more acute angle to the vertical than the face 31. The insert 28 is preferably cut away beginning at a point below the knife edge of the link 29, thus insuring the knife edge always bearing on a flat face of the insert. At each end, each link 39 is provided with an extension of its knife edge construction, which extensions 33 are rounded so as to provide for rotative movement in circular openings 34 formed in two end links 35. Similarly, each of the inserts 24, 27 and 28 has its ends extended, with partial cylindrical surfaces fitting in the bearing openings of the links 35 whereby the parts are held properly assembled while permitting the necessary angular movements that take place, as hereinafter described.

Each of the slideable jaws 15 is provided at its ends with a partial bearing extension 36 and the adjacent portions of the corresponding link 29 have similar partial journal extensions 37, said extensions 36 and 37 working in journal bearing openings 38, in two plates 39-39 fixedly secured to the slideable jaws 15 by suitable screws 40. Along its edge adjacent the slideable jaw 15, each link 29 is formed with a flat bearing face 41 and the opposed jaw is formed with a beveled surface 42 and vertical surface 43, providing a knife edge which bears on the surface 41, so as to provide a fulcrum between the link and jaw.

The table section 112 of the main casting, as best shown in Figure 5, is provided with a centrally disposed and transversely extending slot 44, of inverted T-section. Slideable within the slot 44 are two blocks 45-45, each of which is secured to a slideable jaw 15 by two countersunk machine screws 46-46. In this way, the jaws 15 slide back and forth horizontally on the top of the table section of the main casting and are held from lifting or vertical displacement, as will be understood. It will further be understood that the jaws 15 are of such length as to extend slightly beyond the front and back planes of the main casting, as shown in Figure 5,

whereby to act on any length of fasteners that may be accommodated within the holder 16. The holders 16 are interchangeable, one with another, to accommodate different size fasteners, the holders being held in proper position by a suitable spring-pressed latch 47, shown in Figure 5, the latch being adapted to be depressed to release the holder by a finger piece 48.

The actuators 14 are operated in the following manner. Pivots connected to the lower ends of the actuators 14, as by heavy pins 49-49, are two toggle links 50-50, which in turn are pivotally connected by a heavy pin shaft 51. The latter, at each end, carries a pinion 52, the pinions 52 cooperating with vertically extending fixed racks 53-53 carried by the main casting 10, it being understood that the end walls of the main casting are suitably slotted to permit the up and down movements of the shaft 51, the slots in fact forming guides for this purpose and cooperating with bushings 54-54 applied to the shaft, as shown in Figure 5. At the end of the shaft, at the front of the machine, is secured a two-arm operating lever 55, by which, as will be obvious, the shaft 51 may be raised and lowered. To temporarily hold the shaft 51 in its uppermost position, any suitable means may be provided, such as a spring-pressed pawl 56 carried by the main frame and which engages the shaft 51 below its center, as illustrated in Figure 4.

Each of the screws 22 is formed at its ends with right and left screw threads 57 and with which cooperate preferably octagon nuts 58. Between each nut 58 and the corresponding bearing 23 of the support 13, is a heavy washer 59 having a rounded bearing face 60. Each nut 58 is disposed between a pair of ribs 19 of the support 13 and mounted on each nut is a locking plate 61 which fits relatively snugly between the pair of ribs 19 so as to prevent the nut 58 from turning. By adjusting the nuts 58 relative to the screw threads 57, any desired spacing of the supports 13 may be obtained and, due to the fact that the nuts 58 are of octagonal form, the adjustments may be made to one-eighth of the pitch of the thread and the nuts then held in such adjusted position by slipping on the lock plates 61. At the righthand end of the machine, as viewed in Figure 1, the screws 22 carry sprocket gears 62-62 with which cooperates a sprocket chain 63 to insure simultaneous actuation and one of the screws 22 is provided with a handle 64 for imparting rotation to the screws. The screws 22 are held against endwise movement with respect to the table 12 while being permitted to rotate, preferably by collars 65-65 attached to the screws on opposite sides of the table 12, where the screws pass therethrough. Preferably each support 13 is provided with a fixed plate 66,

as shown best in Figures 1 and 4. These plates 66 are in line with the screws 22, the one at the righthand end, as viewed in Figure 4, being perforated for the accommodation of the screws 22. The lefthand plate 66 serves as a stop for the ends of the screws 22 and both plates further function as a means for forcibly pulling the jaws away from the belt, when the handle 64 is rotated so as to move the jaws outwardly, it being evident that the ends of the screws will engage the lefthand plate 66 and the nuts 58 the righthand end plate, for this purpose, as viewed in Figure 4.

The operation of the device is as follows, first assuming that a length or strip of fasteners has been properly inserted in the holder 16, as shown in Figure 4 and that one end of the belt to which the fastener is to be applied, has been positioned and gauged within the holder, as shown in dotted lines in Figure 4.

The lever 55 is rotated so as to lower the shaft 51 to the full line position of the parts shown in Figure 4, in which condition the lower ends of the actuators 14 are spread apart to the maximum amount. The handle 64 is then rotated so as to effect rotation of the two screws 22—22 and thus bring the clinching jaws 15—15 up against the fasteners and initially enter the prongs of the fasteners into the belt. The lever 55 is then rotated in the opposite direction so as to elevate the shaft 51 and thereby retract the jaws 15 from the fasteners, the amount of retraction being obviously very small.

The shaft 51 will be held in its uppermost position by the spring-pressed pawl 56, previously referred to. Thereupon, the handle 64 is again rotated, so as to turn the screws 22 in the proper direction to bring the supports 13—13 toward each other and until the jaws 15 are again brought up against the prongs of the fasteners. Next, the lever 55 is rotated in a clockwise direction so as to lower the shaft 51 and again spread the lower ends of the actuators 14 and consequently force the jaws 15 toward each other, under very high leverage ratio and, consequently, further embedding the prongs within the belt end. These operations will be repeated as many times as necessary to effect the necessary embedding of the prongs and clinching thereof on the belt end.

During the operations just described, it will be noted that, when the shaft 51 is lowered, the actuators 14 fulcrum on the supports 13 by means of the fulcrum inserts 24 and 27 and an extremely high leverage ratio is obtained, due to the approach to a straight line position of the toggles provided by the upper ends of the actuators 14 and links 29. When the shaft 51 is in its uppermost position, and the screws 22 are rotated to bring the supports 13 toward each other, the supports 13 fulcrum about the pivot pins 17 and

also the actuators 14 fulcrum about their pins 49, at the bottoms thereof. While the pressure obtained by actuation of the actuators 14 during the lowering of the shaft 51 is extremely high, it is obvious that the pressure obtainable by actuating the screws 22 is much less and hence the pressure derived from the operating handle 64 is only utilized in starting the prongs into the belt and thereafter in shifting the jaws 15 to take up the spacing produced after each actuation and retraction of the jaws through the actuators 14.

With the arrangement shown and described, it is obvious that the machine is adapted to apply heavy fasteners to thick belts of any desired width in an expeditious and efficient manner and, further, the necessary adjustments may be made in the machine for applying different size fasteners to different size belts with a powerful squeezing or clinching action always insured, merely by inserting the proper size holder 16.

I have herein shown and described what I now consider the preferred manner of carrying out my invention, but the same is merely illustrative, and I contemplate all changes and modifications that come within the scope of the claims appended hereto.

I claim:

1. In a machine of the character described, the combination with a frame having a table; of clinching jaws directly mounted on said table; actuators for said jaws; operating means for applying power to said actuators at one point thereon; and other independently operating means for applying power to said actuators at a different point thereon.

2. In a machine of the character described for applying metal fasteners, the combination with a frame; of a pair of blocks mounted on said frame to move toward and from each other thereon, each block carrying a relatively long clinching jaw adapted to simultaneously engage a number of fasteners; an actuator for each of said blocks; and two sets of separately operable means for imparting movement to said actuators.

3. In a machine of the character described, the combination with a frame having means to directly support and retain an upwardly facing holder for fasteners in fixed position; of clinching jaws disposed adjacent thereto and movable in a plane above the holder; actuators for said jaws; operating means for applying power to said actuators at one point thereon; and other separate operating means for applying power to said actuators at a different point thereon.

4. In a machine of the character described, the combination with a frame; of an upwardly facing holder for belt fasteners directly supported on and fixed with respect to said frame; a pair of blocks movably mounted on said frame and each carrying a

clinching jaw adapted to simultaneously engage a plurality of fasteners; actuators for said blocks; and two independent sets of operating means for imparting movement to said actuators.

5. In a machine of the character described, the combination with a frame; of slidably mounted clinching jaws; actuators for said jaws; means pivotally connected to each 10 actuator at one point; other means pivotally connected to each actuator at a different point; and operating devices so arranged that either of said pivotal connections is adapted to act as the fulcrum for pivotal movement 15 of the actuators.

6. In a machine of the character described, the combination with a frame having a table; clinching jaws supported directly by said table; means for inducing relative approach 20 and separation of said jaws including an actuator; operating means for applying power to said actuator at one point thereon; and other independently operating means for applying power to said actuator at a different point thereon.

7. In a machine of the character described, the combination with a frame; of a block 30 slidably mounted on a part of said frame and provided with a clinching jaw; an opposing clinching jaw; an actuator for and pivotally connected to said block; and two sets of separately operable means for imparting movement to said actuator.

8. In a machine of the character described, the combination with a frame having a table portion; of jaw-carrying members movably and directly supported on said table portion; actuators for said members; means for operating said actuators in one manner; and 40 separate, independent means for operating said actuators in a different manner.

9. In a machine of the character described, the combination with a frame provided with means for holding the fasteners with the 45 clinching ends thereof projecting and adapted to receive the end of a belt or the like therebetween; of opposed clinching jaws; a pair of actuators each fulcrumed at its end adjacent the jaws; a pivotal connection between each jaw and its corresponding actuator to provide, in effect, a toggle action for the jaws as the same approach each other; and means for imparting pivotal movement to the actuators about said fulcrums.

55. 10. In a machine of the character described, the combination with a frame provided with means for holding the fasteners with the clinching ends thereof projecting and adapted to receive the end of a belt or the like 60 therebetween; of opposed clinching jaws; a pair of movably mounted supports; actuators each fulcrumed at its end adjacent the jaws on a support; a pivotal link connection between each jaw and its actuator; means for 65 imparting pivotal movement to the actuators

about said fulcrums; and means for simultaneously adjusting both of said supports toward and from each other.

11. In a machine of the character described, the combination with a frame provided with 70 means for holding the fasteners with the clinching ends thereof projecting and adapted to receive the end of a belt or the like therebetween; of opposed clinching jaws; a pair of actuators, each fulcrumed at its 75 end adjacent the jaws; a pivotal link connection between each jaw and its corresponding actuator to provide, in effect, a toggle action for the jaws as the same approach each other; and means for imparting pivotal movement 80 to the actuators about said fulcrums, said means including toggle links between the free ends of the actuators.

12. In a machine of the character described, the combination with a frame; of 85 jaw-carrying members slidably and directly mounted on a part of said frame; pivotally mounted actuators for said members; means for moving one set of ends of said actuators toward and from each other; and other means 90 for moving the opposite ends of said actuators from and toward each other.

13. In a machine of the character described, the combination with a frame having a stationary fixed table; of means for holding fasteners mounted on said table; supports pivotally mounted at their lower ends on said frame; actuators pivotally mounted at their upper ends on said supports; clinching jaws operatively connected 100 to the upper ends of said actuators and adapted for movement toward and from each other; means for spreading and retracting the lower ends of said actuators; and means for adjusting the upper ends of the supports toward and from each other, said means including rotatable right and left screws and nuts cooperable therewith.

14. In a machine of the character described, the combination with a frame having a horizontal table; of fastener-holding means secured to the table; a pair of opposed clinching jaws disposed at opposite sides of said means on said table; means for slidably connecting said jaws to the table; and successively independently operable means for imparting a relatively quick low leverage ratio and a relatively slow high leverage ratio movement, respectively, to said jaws.

15. In a machine of the character described, the combination with a frame having a horizontal table; of fastener-holding means secured to the table; opposed clinching jaws disposed at opposite sides of said means on said table; means for slidably connecting said jaws to the table; and successively operable means for imparting a relatively quick low leverage ratio and a relatively slow high leverage ratio movement to said jaws, said successively operable means including pivot- 120
125
130
135

ally mounted supports, actuators pivotally interposed between said supports and jaws and operating devices for said supports and actuators.

5 In witness that I claim the foregoing I have hereunto subscribed my name this 17th day of February, 1930.

GEORGE E. PURPLE.
